UNITED STATES PATENT OFFICE.

GEORGE CHRISTENSON, OF NORTH PLAINFIELD, NEW JERSEY, ASSIGNOR TO JOHNS-MANVILLE INCORPORATED, A CORPORATION OF NEW YORK.

COMPOSITE PISTON-PACKING RING AND METHOD OF MAKING SAME.

Application filed January 11, 1921. Serial No. 436,445.

To all whom it may concern:

Be it known that I, GEORGE CHRISTENSON, a citizen of the United States of America, residing at North Plainfield, county of 5 Somerset, and State of New Jersey, have invented certain new and useful Improvements in Composite Piston-Packing Rings and Methods of Making Same, of which the following is a specification.

10 My invention relates to the formation of composite rings which are suitable for use as cup-shaped packing for pistons where great toughness and durability is required, as in the case of packing for pistons in air- 15 brake cylinders.

According to my invention these rings are formed of a body of plastic vulcanizable material spread upon a sheet of textile fabric and the composite body so formed folded 20 upon itself, shaped into a ring and molded and vulcanized under pressure, with the result that the textile fabric is distributed more of less through the body of the vulcanized material forming the major portion of the 25 ring, said textile fabric serving as a strengthening skeleton therefor.

One embodiment of my invention and of the apparatus and materials for making the same, is illustrated in the accompanying 30 sheet of drawings, in which

Fig. 1 is a cross section of one form of blank from which the completed ring may be made, part being broken away;

Fig. 2 is a similar view of a modified form 35 of blank;

Fig. 3 is a cross section of a mold for changing the shape of the blank, parts being broken away;

Fig. 4 is a similar view of a vulcanizing 40 mold; and

Fig. 5 is a perspective view of a segment of the completed ring.

Throughout the drawings like reference characters indicate like parts.

45 Fig. 1 is a layer of plastic vulcanizable material, such as that set forth in my U. S. Patent No. 1332320, issued March 2nd, 1920, which is spread upon any suitable textile fabric 4. Preferably the textile fabric 50 should be a fairly coarse, strong asbestos cloth. The composite structure so formed having been cut into strips of the proper size is folded one or more times upon itself and the abutting ends of the folded strip 55 fastened together to form a ring of proper

diameter. These strips may be folded so as to bring the fabric 4 on the inside, if only a double fold is employed, as shown in Fig. 1, or may be folded so as to bring the fabric on the outside of the ring, as shown in Fig. 2. 60

The ring so formed is then shaped or molded into the desired form for cup-packing or other purpose for which it is designed, and vulcanized under pressure in this shape. 65

Preferably in forming piston packing I first compress the blank between the curved mold 2 and cooperating former 3, as shown in Fig. 3, and then transfer the cup-shaped ring so formed to the vulcanizing die 5, in 70 which it is compressed, and given its final form by the corresponding cooperating former 6, as shown in Fig. 4. After subjection to the proper degree of heat to vulcanize the plastic material, the ring may be removed, producing the completed packing ring 7 shown in Fig. 5. 75

In the completed packing ring the textile fabric is imbedded and more or less disseminated by the action of the plastic material 80 which has been forced between the threads of the fabric by the great pressure of the molds, and the textile fabric thereby becomes a supporting skeleton for the completed ring, which adds greatly to its toughness and tensile strength and its resistance to wear. 85

This fabric arranged as a skeleton in the ring is indicated at 4 in Figs. 3, 4 and 5, the arrangement being that which would be produced by operating on the form of blank 90 shown in Fig. 1. Of course if the blank shown in Fig. 2 were employed, the two sections of the skeleton fabric would be somewhat more separated and located nearer the external surfaces of the completed packing ring. 95

Of course more than two folds of the original fabric might be employed in making the rings, if desired, and other means of molding or shaping the same might be 100 employed.

I claim:

1. The method of forming a composite ring suitable for use as a cup-shaped piston packing or the like, which comprises the following steps: first, applying to a sheet of woven fabric a layer of plastic material capable of being vulcanized of a greater thickness than that of the fabric; second, 105 folding the composite fabric so formed upon 110

2

itself and arranging such folded fabric in an annular form; third, molding said ring into the desired shape and vulcanizing the plastic material, whereby the textile material becomes imbedded in the vulcanized mass and forms a skeleton support therefor in a relatively thick completed ring.

2. A product of the herein described process, being a composite ring suitable for use

as a cup-shaped piston-packing or the like, ¹⁰ composed of a relatively thick mass of vulcanized material having a folded sheet of relatively thin textile fabric imbedded therein.

GEORGE CHRISTENSON.
